OR D17,102 EX

DESIGN.

—o—
J. ROGERS.

GROUP OF STATUARY.

No. 17,102.

Patented Feb. 8, 1887

UNITED STATES PATENT OFFICE.

JOHN ROGERS, OF NEW CANAAN, CONNECTICUT.

DESIGN FOR A GROUP OF STATUARY.

SPECIFICATION forming part of Design No. 17,102, dated February 8, 1887.

Application filed January 3, 1887. Serial No. 223,330. Term of patent 14 years.

To all whom it may concern:

Be it known that I, JOHN ROGERS, a citizen of the United States, residing at New Canaan, in the county of Fairfield and State of Connecticut, have invented and produced a new and original Design for a Group of Statuary, of which the following is a specification, reference being had to the accompanying drawing, forming part thereof.

The group consists of a man on horseback and a girl behind him, on the same horse, and another man walking beside her. They are dressed in Puritan costume. The man on horseback wears a conical hat, a jacket, knee-breeches, and high boots. He has an open book in his left hand and is in the act of turning the leaves with his right hand. His head is turned toward the front as he looks to see what is going on behind him. The girl has a

cloak over her shoulders. With her left hand she is taking an apple that the man by her side is offering her. This man is dressed in jacket and knee-breeches, and carries his hat full of apples under his arm, while he offers the girl one with his right hand. The horse is nibbling the leaves by the roadside. The name marked on the base of the group is the "Elder's Daughter."

I claim—

The design for a group of statuary herein shown and described, representing a man and girl riding on a horse and a man walking by their side.

JOHN ROGERS.
